UNITED STATES PATENT OFFICE.

KIRK BROWN, OF MONTCLAIR, NEW JERSEY, ASSIGNOR TO CONDENSITE COMPANY OF AMERICA, OF BLOOMFIELD, NEW JERSEY, A CORPORATION OF NEW JERSEY.

CARBOY.

1,371,220.

Specification of Letters Patent. Patented Mar. 15, 1921.

Application filed November 13, 1920. Serial No. 423,904.

To all whom it may concern:

Be it known that I, KIRK BROWN, a citizen of the United States, residing at Montclair, in the county of Essex and State of 5 New Jersey, have invented certain new and useful Improvements in Carboys, of which the following is a specification.

My invention relates to improvements in carboys. The object of my invention is to 10 provide an inexpensive and simple type of construction whereby the neck of the bottle protruding from the top of the carboy is protected from damage and at the same time a structure is presented such that the carboys may be piled directly on top of each 15 other for transportation or storage.

The form of carboy commonly used comprises a rectangular casing having a fixed top through an opening in which extends the 20 neck of the bottle contained therein. The neck of the bottle in the form of device referred to, is protected by a cover device which is nailed to the top of the carboy on each side of the bottle neck, so as to extend 25 slantingly above the neck is the form of an A. Such covers are frequently lost and not returned with the carboy when the latter is returned to the manufacturer of acid or other liquid contained in the bottle. Also in removing such covers the user will sometimes 30 force the same off so carelessly as to break the neck of the bottle, or when replacing the same will drive the nails into the bottle.

Another difficulty encountered in the use 35 of the form of construction referred to consists in the fact that the A shaped guards or covers make it necessary to pack the carboys in a car or in storage in pyramid formation, thus limiting the number of carboys 40 that can be packed in a given space, and making it necessary to trim the car very carefully with timber to keep the carboys from moving and shearing off their necks.

Other forms of carboys have been proposed 45 in which the neck is protected by a hinged cover, but such a construction is relatively expensive, and the cover is in the way when liquid is poured from the bottle. Other types of carboys which have been 50 proposed require special shapes for the top of the container, which is objectionable, or have detachable covers or other parts which are likely to get lost.

I overcome these various difficulties by the 55 provision of a simple form of framework

which may be permanently secured to the usual form of rectangular carboy, this framework carrying a pair of horizontal members above the level of the top of the bottle neck and on opposite sides thereof. 60 Preferably, four upright pieces of wood are employed, two secured to each of two opposite sides of the container to extend above the top of the bottle neck. A pair of horizontal members are fastened on the tops of 65 these vertical members so as to provide a deck or upper surface on which another similar carboy may be placed. By means of this simple construction, the carboys may be piled on top of each other in the form of 70 a compact parallelogram instead of a pyramid, with the result that from fifty to sixty per cent. more carboys may be put in one car, and with the necessity of using less timber than in the case of the prior construction 75 having the A shaped guards referred to. My improved construction makes a permanent addition to the common form of carboy, and one which does not interfere with pouring from the bottle.

In order that my invention may be more clearly understood, attention is hereby directed to the accompanying drawings forming part of this application and illustrating one embodiment of my invention. In the drawings, Figure 1 represents a side elevation of a carboy embodying my invention; Fig. 2 is an end elevation of the same; Fig. 3 is a top plan view of the same; and Fig. 4 is an end elevation of a number of carboys stacked 80 for shipping.

Referring to the drawings, the container 1 is the usual form of rectangular wooden construction having a top member 2 through an opening in which extends the neck 3^a of 95 the bottle 3' contained therein. I have illustrated the usual common construction in dotted lines, the members which are added by my invention being shown in full lines. In the usual construction, carboys are 100 packed in boxes such as that indicated at 1 by surrounding the same with corrugated wood or kieselguhr or other suitable packing material. This is common construction, and I have not deemed it necessary to illustrate the same herein.

In accordance with my invention, uprights 3, 3 are secured to one vertical surface of the container 1, and similar uprights 4 are secured to the opposite side or vertical sur- 110

face of container 1. The strips 3, 4 may be secured to container 1, to extend upwardly adjacent to the vertical edges of the same by means of nails 5 or other suitable securing devices. The uprights 3, 4 will extend above the top of container 1 a distance slightly greater than the height of the bottle neck 3^a above the top 2.

Cross pieces 6, 6 are secured across the tops of vertical members 3 and 4 as shown, these cross members suitably being secured by nails 7 to the tops of the vertical members. The members 3, 4 and 6 may be rectangular strips of wood of suitable dimensions.

Such carboys are usually provided with cleats 8 on the sides thereof to aid in lifting the same and with stiffening members 9 extending across the bottom of the container, and such a construction is shown in the drawings.

It will be noted from Fig. 4 that a plurality of carboys may be piled directly one upon another for purposes of shipping, as stated. It will also be noted that the added construction will not interfere in any way with pouring fluid from the bottles. It will also be noted that the added construction does not interfere with the removal of the top 2 of the container 1, it being desirable to remove the top 2 from time to time when the packing material surrounding the bottle has to be renewed.

Not only will my construction contribute greatly to the economical use of transportation facilities, but also because of the fact that the construction contains no detachable or loose parts, it will be noted that the

same will greatly facilitate complying with governmental requirements in regard to transportation as defined by the bureau of explosives.

What I claim is:—

1. A carboy comprising a rectangular container having a top with an opening 45 therein through which extends the neck of the bottle contained therein, upright members secured to sides of the container and extending above the top of the bottle neck, and horizontal members secured to the upper ends of said upright members to form a surface on which a similar carboy may be stood, in shipping the same.

2. A carboy comprising a rectangular container having a top with an opening 55 therein through which extends the neck of the bottle contained therein, a pair of vertical members secured to each of two opposite sides of the container and extending above the top of the bottle neck, and a pair 60 of parallel horizontal members secured to the upper ends of said vertical members.

3. A carboy comprising a container having a top with an opening therein through which extends the neck of the bottle contained therein, and a framework comprising horizontal members above the neck of the bottle, on opposite sides thereof, and members supporting the same from and secured to said container.

This specification signed and witnessed this 8th day of November, 1920.

KIRK BROWN.
